HEAT EXCHANGE DEVICE

Arthur B. Modine, Racine, Wis., assignor to Modine Manufacturing Company, Racine, Wis., a corporation of Wisconsin

Application May 18, 1934, Serial No. 726,303

1 Claim. (Cl. 257—130)

This invention relates to heat exchange devices, and particularly to a device wherein a core is provided and designed to permit the passage of air therethrough.

5 One object of the present invention is to improve the weight efficiency of the material employed in a heat exchange device, determined by the relationship between the cooling capacity and the weight of the material.

10 Another object of the invention is to provide a device of the character described wherein a substantial saving in materials may be had, and consequently a substantial reduction in the ultimate cost of production obtained.

15 A further object of the invention is to provide a heat exchange device of less material and reduced cost, and wherein the heat exchange capacity of the device as a whole, is maintained, and is substantially equal to that of a device of commonplace design.

20 A still further object of the invention is to improve devices of the character described in sundry details hereinafter referred to and particularly pointed out in the appended claim.

25 Several species of the present invention are embodied and shown for illustrative purposes in the accompanying drawing, in which:

Fig. 1 is a front view of a motor vehicle radiator unit typifying a heat exchange device embodying novel features characterizing the 30 present invention;

Fig. 2 is a fragmentary sectional elevational view of a portion of the structure illustrated in Fig. 1, and taken substantially as indicated by the line 2—2 thereof;

Fig. 3 is a plan sectional view taken substantially as indicated by the line 3—3 of Fig. 2;

Fig. 4 is a fragmentary plan sectional view similar to Fig. 3 illustrating a modified construction and arrangement which the present invention may assume; and

Fig. 5 is a fragmentary sectional elevation view similar to Fig. 2 illustrating a further modified construction and arrangement embodying features of the present invention.

In Fig. 1 of the drawing, the present invention is shown as applied to a heat exchange device having a shell, indicated as a whole by the numeral 6, comprising side portions 7 and upper and lower tanks or headers 8 and 9, respectively, and, as illustrated in Figs. 1, 2 and 3, the present invention contemplates a core, indicated as a whole by the numeral 11, positioned within the shell 6 between the headers 8 and 9, the core 11 having open portions for the passage of air there-

through in the direction indicated by the arrows in the respective figures of the drawing.

The core illustrated in Figs. 1, 2 and 3 comprises a plurality of vertically spaced fins of substantially uniform thickness having a plurality 5 of series of apertures 13 formed therein adapted, respectively, to receive a plurality of series of vertically disposed fluid conducting tubes 14 for conducting heated fluid between the headers 8 and 9, the tubes of the respective series being 10 relatively spaced longitudinally of the fins, and the respective series of tubes being spaced transversely of the fins to provide a plurality of related regions or zones indicated, respectively, and for convenience in the further description of the 15 present invention, by the characters A, B and C, the tubes 14 of zone B being spaced further apart and consequently of less number than in the first or receiving zone A, and the tubes in zone C being spaced still further apart and consequently of still lesser number than in zone B. 20

It is of course well known that the air entering zone A at the receiving side of the core is of maximum temperature potential, i. e., the relative difference in temperature between the air 25 and the heated surface, or the ability of the air to absorb heat, permits a maximum exchange of heat from the heated surface to the air in its passage through zone A. Assuming that the most desirable spacing of tubes and fins and fin 30 material thickness in zone A has been established, it will be evident that by passing the air through zone A, its temperature potential or its ability to absorb heat is lowered and as a consequence the air upon entering zone B is incapable 35 of absorbing a like degree of heat from the heated surface in this zone. For the reason that less duty therefore is exacted upon the heat transfer ability of the heated surfaces in zone B, the spacing of the tubes in zone B may be increased and 40 the number of tubes reduced. This results in an increase of the weight efficiency of the structure for the reason that more material is displaced than that which is proportionate to the resultant loss in heat transfer capacity of the 45 structure through the reduction of the number of tubes.

Owing to the conditions similar to those above described, the potential of the air after passing through zone B is reduced still further, and by 50 reason of the temperature of the air more nearly approaching that of the tubes, the air upon entering zone C is further incapable of absorbing any great degree of heat from the tubes 14 of zone C regardless of their number, thus permitting an 55

increased spacing and a consequent reduction in the number of tubes in zone C according to the reduction in temperature potential of the air after passing through zone B and as it enters zone C, 5 all without materially lessening the heat exchange capacity of the device as a whole.

It will be observed from the foregoing description that owing to the successive reduction in the temperature potential of the air in its passage 10 through the respective zones A, B and C of the core, the spacing of the tubes in the respective zones may be increased and the number of tubes reduced, successively, in the respective zones from the receiving side to the discharge side of the core, or in other words, in the direction of air flow therethrough, and according to the successive reduction in the temperature potential of the air as it passes through the core, thus permitting a decrease, successively, in the quantity of 15 material used in the respective zones, thereby increasing the weight efficiency of the material employed, and substantially lowering the cost of production, but without materially reducing the heat exchange capacity of the device as a whole.

25 In the structure illustrated in Fig. 4, the core 11' is formed of fins 12', which are provided with a plurality of spaced apertures 13' adapted, respectively, to receive a plurality of series of vertically disposed fluid conducting tubes 14', the 30 tubes of the respective series being spaced longitudinally of the fins while the respective series of tubes are spaced transversely of the fins to provide a plurality of related regions or zones indicated, respectively as A', B' and C' in a manner 35 similar to that referred to in connection with the structure illustrated in Figs. 1, 2 and 3.

It will be noted, by referring to Fig. 4, that while the tubes 14' in all of the zones A', B' and C', are substantially uniformly spaced, the tubes 40 of the series in the respective zones are of different cross-sectional area, the tubes in zone B' being smaller than in the first or receiving zone A', and those in zone C' being smaller than the tubes in zone B', in other words, the tubes of the 45 respective series in zones A', B' and C', are reduced, successively, in cross-sectional area, proceeding in the direction of air flow, or from the receiving side to the discharge side of the core.

It will be observed also that by reason of the 50 structure characterizing Fig. 4, the quantity of material used in the respective zones decreases, successively, in the direction of air flow according to the reduction in the temperature potential of the air as it passes through the core, thereby 55 also increasing the weight efficiency of the ma-

terial employed and substantially lowering the cost of production without materially reducing the heat exchange capacity of the device as a whole.

In the construction shown in Fig. 5, similar 5 results may be obtained by providing a core 11'' with a plurality of fins 12'' having fluid conducting tubes 14'' extending therethrough, all of the tubes 14'' of Fig. 5, being of substantially uniform size and cross-section, and being uniformly 10 spaced in series to form related regions or zones A'', B'' and C''. In Fig. 5, the air receiving edges of the fins 12'' are thicker than the discharge edge portions, and the upper and lower faces of the fins are inclined or tapered toward each other 15 from adjacent the air receiving side of the core 11'' to adjacent the discharge side thereof, thereby also providing a structure wherein the quantity of material used in the respective zones A'', B'' and C'' decreases, successively, in the direction 20 of air flow, approximately according to the reduction in the temperature potential of the air as it passes through the core.

It will be apparent from the foregoing description that the present invention provides a novel 25 construction and arrangement whereby the weight efficiency of the material employed is increased, and substantial saving in the cost of production of a heat exchange device of the character described is obtained, without materially 30 lowering the effective heat exchange capacity of the device.

Obviously, the present invention is not limited to the precise construction and arrangement shown and described, as the same may be variously modified without departing from the spirit and scope of the invention as set forth in the appended claim.

What I claim as new and desire to secure by Letters Patent is:

A heat exchange device having a core provided with open portions for the passage of air therethrough, said core comprising a plurality of substantially uniformly spaced fins and a plurality of series of relatively spaced fluid conducting 45 tubes extending through said fins, said series of tubes being spaced transversely of the fins to provide a plurality of zones between the air receiving side and the discharge side of said core, the tubes of the respective series being substantially uniformly spaced and of less cross-sectional area, successively, in the respective zones beyond the first zone proceeding in the direction of air flow through the core.

ARTHUR B. MODINE. 55
